UNITED STATES PATENT OFFICE.

REY HOLLIS, OF SANTA BARBARA, CALIFORNIA.

CUSHION FOR HEADRESTS.

1,401,406.

Specification of Letters Patent. Patented Dec. 27, 1921.

Application filed February 14, 1921. Serial No. 444,633.

To all whom it may concern:

Be it known that I, REY HOLLIS, a citizen of the United States, residing at Santa Barbara, in the county of Santa Barbara and 5 State of California, have invented a new and useful Cushion for Headrests, of which the following is a specification.

This invention relates to cushions particularly adapted to be used on the head rests of 10 chairs of the character employed in the dental and other professions, and an object of the invention is to add to the comfort of the patient occupying the chair.

Another object is the provision of a sanitary covering for the head rest.

Another object is to provide a cushion of this character that can be readily detached from the head rest when soiled, laundered and again attached to the head rest.

20 Another object is to detachably connect the pad to the attaching members so as to facilitate laundering of either the pad or the attaching members or both.

The accompanying drawings illustrate the 25 invention:

Figure 1 is a longitudinal view, mainly in mid section, of a cushion constructed in accordance with the provisions of this invention and attached to a head rest shown in 30 elevation.

Fig. 2 is an inverted plan view of the cushion shown in Fig. 1 opened out flat, one of the attaching members being expanded to its maximum diameter and the other one 35 being folded upon itself to expose to view the fastening members for detachably connecting the pad to the attaching members.

There is provided a pad comprising a cover or casing 1 and filling 2 therefor of cotton, 40 hair or other suitable material. The pad may be finished in any desired manner and, in the instance shown, it is quilted as indicated at 3. The pad, in the instance illustrated, is rectangular, but it may be of any 45 other suitable shape.

Fastened to the cover 1 of the pad are attaching members 4 which, in this instance, are in the form of cup-shape receptacles. Preferably, though not necessarily, the members 50 4 are detachably connected with the pad and, therefore, the under face of the cover 1 and the upper faces of the members 4 are provided with coöperating fasteners 5, 6 which, in this instance, constitute the well-known snap or glove fasteners.

The members 4 are positioned substan-

tially midway between the transverse medial line of the pad and the respective ends thereof and they are adapted to receive the knob-like head rests *a* commonly provided 60 on the chairs occupied by patients in the dental and medical professions. These head rests *a* are generally adjustably mounted on a bent rod *b* in spaced relation as shown in Fig. 1 so that the back of the patient's head 65 will lie between the head rests.

The members 4 are preferably adjustable in diameter to fit different shapes and sizes of head rests, and I secure adjustability, in this instance, by providing each of the 70 members 4 near its rim with a drawstring 7. The drawstrings may be selectively positioned according to the size of the head rests, and for this purpose there are provided a plurality of ways 8, 9, 10 in the 75 hems 11 defining the rims of the members 4. The ways 8, 9, 10 are different distances from the margins of the mouths of the members 4 so that the drawstring will be placed in the way 8 for a smaller head rest, in the 80 way 9 for a head rest of intermediate size and in the way 10 for a larger head rest.

In practice, the invention will be applied to the head rests as shown in Fig. 1 and the drawstrings will be drawn taut and tied 85 to securely fasten the cushion in place. When the pad 1, 2 becomes soiled it may be unsnapped from the fasteners 6 and a clean pad of similar construction substituted in its stead while the first pad is being laundered. Or, if the attaching members 4 also require laundering, they as well as the pad will be removed from the head rest and a clean cushion complete substituted while the detached pad and its attaching members 90 are being laundered. In this manner a dentist or other person employing this character of chair for his patients may add to the physical and mental comfort and well-being of his patients with small expense. If 100 desired, a clean towel may be placed over the cushion for each patient occupying the chair, thus keeping the cushion clean longer and avoiding any chance of infection of one patient by another.

I claim:

1. In a cushion for head rest, a pad, and attaching members fastened to the under surface of the pad and provided with means to contract them.

2. In a cushion for head rest, a pad, and receptacles attached to the under surface of

the pad and adapted to receive the head rests of a dental chair.

3. In a cushion for head rest, a pad, receptacles adapted to receive the head rests of a dental chair, and means detachably fastening the pad to the receptacle.

4. In a cushion for head rest, a pad, receptacles attached to the under surface of the pad and adapted to receive the head rests of a dental chair, and means to contract the receptacles.

5. In a cushion for head rest, a pad, and

means on the under face of the pad between the transverse medial line of the pad and the ends thereof to detachably secure the pad to the knob-like head rests of a dental chair.

Signed at Santa Barbara, California, this 7th day of February, 1921.

REY HOLLIS.
